UNITED STATES PATENT OFFICE.

RAYMOND CALPIN, OF EVERETT, MASSACHUSETTS, ASSIGNOR TO A. S. CAMPBELL COMPANY, OF EAST BOSTON, MASSACHUSETTS, A CORPORATION OF MASSACHUSETTS.

CURTAIN-WINDOW INSTALLATION.

Application filed January 14, 1925. Serial No. 2,289.

This invention aims to provide an improved curtain window installation, and improved frame members for the same.

In the drawings, which illustrate a preferred embodiment of my invention:

Fig. 1 is a rear elevation view of the installation as applied to a flexible curtain;

Fig. 2 is an enlarged section on the line 2—2 of Fig. 1, the center part being broken away;

Fig. 3 is an elevation view of the prong-presenting frame member;

Fig. 4 is a fragmentary side elevation of a portion of the installation showing the end of the glass-holding frame removed to permit removal of the glass;

Fig. 5 is an elevation view of the inserts for the prong-presenting frame;

Fig. 6 is an underside view of the glass-holding frame part;

Fig. 7 is an enlarged fragmentary view of a portion of the glass-holding frame part showing one of the notched prong-receiving slots;

Fig. 8 is a cross-section of one end of the installation, showing a slightly bent prong being guided into the prong-receiving slot;

Fig. 9 is a section similar to Fig. 8, showing the frame parts just prior to bending the attaching prongs;

Figs. 10, 11 and 12 illustrate the method of securing the inserts within the prong-presenting frame member;

Fig. 13 is an enlarged section on the line 13—13 of Fig. 3;

Fig. 14 is an enlarged section on the line 14—14 of Fig. 3, showing an attaching prong presented by the insert at one corner of the frame part;

Fig. 15 is an elevation view of the glass-holding frame part;

Fig. 16 includes enlarged sectional views on the line 16—16 of Fig. 15, showing the prong-concealing flange of the removable end before and after it is clenched in plate;

Fig. 17 is an enlarged section on the line 17—17 of Fig. 15, showing a fabric-gripping spur; and

Fig. 18 is an enlarged section on the line 18—18 of Fig. 1, showing an attaching screw in elevation.

Referring to the drawings, I have shown a curtain window installation which is particularly, though not exclusively, useful as

a curtain window installation for automobiles.

The installation includes a curtain fabric 1, a glass 2 and a plurality of metal frame parts secured to the curtain for holding the glass in place relative thereto. In installations of the kind illustrated, it is particularly helpful to secure as many of the metal frame parts permanently to the curtain fabric as possible. To this end, I have provided one of the frame parts with a removable end portion, which may be removed from the installation independently of the rest of the frame parts, thereby permitting the glass to be slid out of engagement with the rest of the frame, as more fully herein-after described.

The metal frame parts include a prong-presenting frame unit 3 located at the outer face of the curtain 1 and a glass-holding prong-receiving frame member 4 secured to the inner face of the curtain, as illustrated in Fig. 2. The prong-presenting frame unit 3 includes an outer frame part 5 (Figs. 2 and 3) presenting at the exposed face thereof a central stiffening rib 6, and an inner frame part or insert 7. This inner frame part is preferably, as illustrated in Fig. 5, formed from sheet metal and comprises four separate pieces secured to the outer frame part 5 by flanges 8 and 8^a extending inwardly over the insert 7 from the inner and outer edges of the outer frame member 5. These flanges are cut away at the corners of the frame to permit bending thereof at the straight sides of the frames. The flange 8 extending from the inner edge of the frame part 5 presents, at its free edge, a plurality of outwardly extending prongs 9 for securing the frame unit 3 to the curtain 1.

The inserts are important inasmuch as they strengthen the frame part 5, back-support the attaching prongs 9 and present, between the flanges 8 and 8^a at the corners of the frame unit 3, attaching prongs 10 and screw-receiving portions 11, as best illustrated in Figs. 2, 13 and 14, the purposes of which are hereinafter described.

Figs. 1 through 14 include sections which illustrate the method of assembling the frame unit 3. The pieces of the insert are placed between the upstanding flanges 7 and 8, as illustrated in Fig. 10, and the flanges are then bent inwardly, Fig. 11,

until they are pressed against the face of the insert as illustrated in Figs. 12, 13 and 14. The glass-holding frame 4 presents a relatively wide fabric-gripping surface 12 in which are provided a plurality of notched prong-receiving slots 13 (Figs. 6 and 7), a normally slightly inwardly bent flange 14 at the outer edge of the frame and an angular portion 15 at the inner edge of the frame 10 providing a glass-receiving recess, as illustrated in Figs. 2, 6 and 8. One end 16 of the glass-holding frame part is separated from the rest of the frame and this end includes the rounded corners at that end thereof as illustrated in Figs. 1, 6 and 15. This frame part 4 is pressed from a single sheet of metal, as illustrated in Figs. 15 through 17, and the flange 14 extends outwardly therefrom (Fig. 16). The removable portion 16 is cut 20 off from the rest of the frame 4 and the flange 14 is bent inwardly against the portion 12, while the flange 14 of the remainder of the frame is bent slightly inwardly, as illustrated in Fig. 17. Thus the frame parts 25 are made ready for assembly to the curtain fabric 1.

Assembly of the installation is as follows:—first the frame unit 3 is placed upon a table or bench, the prongs projecting upwardly therefrom. The curtain fabric 1 is then placed over the frame and the prongs pressed through the fabric. The frame part 4, except the removable end, is then placed over the curtain so that the prongs 9 engage 30 the slots 13 and so that the attaching prongs 10, presented by the inserts 7, engage the slots 13 at the rounded corners. The flanges 14 are thereafter bent downwardly and these flanges engage and bend the prongs 9 40 against the upper face of the fabric-engaging portion 12 of the frame part 4 (Fig. 2). The prongs 10, which are exposed at the corners, may then be pressed into engagement with the frame part 4. Thus the frame 45 members are “permanently” secured to the curtain fabric 1 and need not be separated therefrom when the glass 2 is being changed. A firm grip on the curtain fabric 1 between the frame members 3 and 4 is provided by 50 forming a plurality of spurs 20 (Figs. 6 and 17), which grip the fabric. The prongs 9, which are located at that end of the frame which is removable, are bent against the curtain fabric 1 (Fig. 2) and the glass may 55 then be slid into the groove provided between the frame parts 3 and 4, the fabric providing a cushion from one side of the glass. After the glass is in place, the removable end 16 is placed in position and self-tapping screws 17 are passed through openings in bosses 18, 18 provided in the corners of the removable end (Figs. 1 and 18) and are threaded into the screw-receiving portions 11 presented by the inserts 7. Thus 60 the removable end 16 is held in place and

the glass cannot be removed from the installation until the screws are taken out and the end 16 removed. After the installation is completely assembled, the curtain fabric 1 over the glass may be cut out by 70 drawing a sharp pointed instrument along the inner edge of the frame unit 3 in the usual manner and the installation is then ready for use.

The notches 19, 19 at each side of the prong-receiving slots 13 are important because they provide simple, but very efficient, means for guiding slightly bent or misaligned prongs into the narrower portions of the slot as illustrated in Figs. 7, 8 and 9. 80 Thus the assembly of the frame parts is greatly simplified and much time is saved. Slightly bent prongs (Fig. 8) are automatically straightened and guided into the slots (Fig. 9) by these notches. 85

While I have shown and described a preferred embodiment of my invention, it will be understood that changes involving omission, substitution, alteration and even reversal of parts may be made without departing from the scope of my invention, 90 which is best defined in the following claims.

Claims—

1. A curtain window installation comprising, in combination, a curtain fabric, a glass and frame members secured to said curtain to hold said glass, one of said frame members located at one side of the curtain fabric and including an insert presenting attaching means extending therefrom and 100 piercing the fabric and engaged with the other frame member located at the opposite side of the curtain fabric to secure the frame members together and grip the curtain fabric therebetween, said other frame member having a portion thereof adjustably connected to the remainder of the installation for permitting withdrawal and insertion of the glass without disturbing the said remainder of the installation. 110

2. A curtain window installation comprising, in combination, a curtain fabric, a glass, pressed metal frame members secured to opposite sides of said curtain to hold said glass in assembly therewith, one of said frame members including an insert presenting attaching prongs for engagement with the other frame part, and said last mentioned frame member having a removable end portion adapted to be held in place by a plurality of attaching elements passing through said removable end and engaging said insert. 115

3. A curtain window installation comprising, in combination, a curtain fabric, a glass held in position relative to said curtain by a frame unit located at one side of the curtain and a glass-holding frame part located at the other side of the curtain, said frame unit comprising an outer frame member enclosing an insert, and said outer frame member 125

- and insert presenting attaching means for engagement with said glass-holding frame part to secure said frame members to opposite sides of the curtain said glass-holding
- 5 frame part having a removable portion for permitting withdrawal and insertion of the glass without disturbing the remainder of the installation and means for removably fastening said removable portion to said
- 10 frame unit.
4. A curtain window installation comprising, in combination, a curtain fabric, a glass, a prong-presenting frame unit at one side of the fabric, and a glass-holding frame
- 15 member having a removable end at the opposite side of the curtain, said frame unit including an insert formed from a plurality of flat metal strips presenting attaching prongs at one end of the unit cooperating
- 20 with the prongs presented by the outer frame part of said unit to secure the glass-holding frame member, except the removable end, and the prong-presenting frame unit permanently to the curtain, and said
- 25 insert presenting at the opposite end of said unit a plurality of screw-receiving portions for receiving screws to secure said removable end in place, thereby to prevent removal of said glass.
- 30 5. A curtain window frame element comprising a unit having a reinforcing insert held in place within an outer frame part by flanges extending over the edges of said insert, one of said flanges presenting a plurality of attaching prongs back-supported by said insert.
6. A curtain window frame unit including an outer frame part, and an inner part, said inner part formed from a plurality of
- 35 separate parts secured to said outer part by flanges extending over the inner part from each edge of the outer part, said flanges spaced apart at the corners of the unit to expose attaching prongs at one end of the
- unit which are presented by the inner part 45 and means presented by said insert for assisting in securing said frame element as a part of a curtain window installation.
7. A curtain window frame unit including an outer frame part and an inner part, said 50 inner part formed from a plurality of separate parts secured to said outer part by flanges extending over the inner part from each edge of the outer part, said flanges spaced apart at the corners to permit prongs 55 to be exposed at some of the corners and screw-receiving portions at the other corners of the unit.
8. A curtain window frame unit including an outer frame part and an inner part, said 60 inner part formed from a plurality of separate parts secured to said outer part by flanges extending over the inner part from each edge of the outer part, said flanges spaced apart at the corners to permit a plurality of prongs and screw-receiving portions 65 to be exposed at the corners of the unit and a plurality of attaching prongs presented at the edge of one of said flanges and back-supported by said inner part, said outer frame being spaced away from said inner part beneath said prongs.
- 70 9. A curtain window frame unit including an outer frame part and an inner part, said 75 inner part being overlain by flanges extending inwardly from the peripheral edges of said outer frame part, attaching means extending from said frame unit adjacent to the edges of said flanges, and means presented by said inner part at the 80 corners of said frame unit between widely separated edges of the flange portions for assisting in securing the frame unit as part of a curtain window installation.
- In testimony whereof, I have signed my 85 name to this specification.

RAYMOND CALPIN.

CERTIFICATE OF CORRECTION.

Patent No. 1,671,062.

Granted May 22, 1928, to

RAYMOND CALPIN.

It is hereby certified that error appears in the printed specification of the above numbered patent requiring correction as follows: Page 3, line 36, claim 5, after the word "insert" and before the period insert the words "and means presented by said insert for assisting in securing said frame element as a part of a curtain window installation"; same page, lines 46 to 48, claim 6, strike out the words "and means presented by said insert for assisting in securing said frame element as a part of a curtain window installation"; and that the said Letters Patent should be read with these corrections therein that the same may conform to the record of the case in the Patent Office.

Signed and sealed this 19th day of June, A. D. 1928.
